UNITED STATES PATENT OFFICE

MAURICE FRANK HUTCHISON, OF HERNDON, VIRGINIA; CLARE E. HUTCHISON
ADMINISTRATRIX OF SAID MAURICE FRANK HUTCHISON, DECEASED

MODULATOR FOR HEATING SYSTEMS

Application filed April 1, 1920. Serial No. 370,471.

This invention relates to heating systems and has for its object the provision of simple and inexpensive means whereby the occupant of a room may have the temperature of the room automatically maintained at any desired degree. This stated object and other incidental objects which will appear in the course of the following description are attained in the use of such mechanism as is illustrated in the accompanying drawings and the invention resides in certain novel features which will be particularly pointed out in the appended claims.

In the drawings—

Fig. 1 is an elevation of a radiator having one embodiment of my invention applied thereto.

Fig. 2 is an enlarged view of the attachment shown in Fig. 1, parts being shown in section.

Fig. 3 is a plan view of the thermostat.

Fig. 4 is an elevation of a radiator equipped with another form of the invention.

Fig. 5 is an enlarged sectional elevation of the thermostatic valve shown in Fig. 4.

Fig. 6 is a plan view of the thermostat with the handle in section.

The radiator 1 is of the usual or any preferred form and in both illustrated applications of the invention is part of a one-pipe steam or vapor heating system, the steam or vapor for heating the radiator being supplied through a pipe 2 and the water of condensation returning to the boiler through the same pipe. A cut-off valve 3 is interposed in the pipe 2 in the usual manner.

As is well known, the radiator is heated section by section as the heating agent enters and the air in the radiator must be driven out or the entrance of the heating agent will be arrested, a vent 4 being provided on that section of the radiator remote from the supply pipe 2, to permit escape of the trapped air. In the form of the invention shown in Figs. 1, 2 and 3, the vent tube 4 is provided at its outer end with a casing 5, which is preferably a shallow cylinder in construction, as shown in Fig. 2, and a port 6 in the side of the tube 4 establishes communication between the interior of the cylinder and the bore of the tube.

A valve 7 is provided to close or open the port 6, and said valve is carried by a flexible hollow disk or diaphragm 8, housed within the casing and resting at its peripheral edge upon an internal annular shoulder 9 on the wall of the casing. A nipple 10' leads from said diaphragm and a spring 10'' is coiled around said nipple between the diaphragm and the top of the casing, as shown in Fig. 2, to hold the diaphragm to its seat on the shoulder 9, with the valve 7 in proper alignment with the port 6. A flexible pipe 10 is connected to and communicates with the nipple and this pipe should be long enough to extend entirely across the radiator. The free extremity of this pipe is bent on itself to form a spiral coil 11 which may bear against the side of a radiator section and the pipe is filled with a thermostatic liquid, such as mercury, which in expanding will exert pressure between the closed end of the pipe and the diaphragm. A helical spring 12 is attached to one side of the coil 11, to frictionally engage the radiator section adjacent the section against which the coil bears so as to hold the coil in contact with the latter section. Clips 13 attach to the coil 11 a ring 14, from which a shank 15 extends, said shank terminating in a handle 16 of spiral formation to permit free circulation of air therethrough so that it will not become hot and may be grasped without discomfort.

The use of the device is thought to be evident. The coil 11 may be placed against any section of the radiator and will be held in the set position by the spring 12, bearing against the adjacent section, Fig. 1, showing the coil against the third section and the spring bearing against the second section. The valve 3 being open the heating agent will fill the first three sections of the radiator, driving out the air contained therein through the vent tube 4, it being noted that the nipple 10' is spaced away from the top of the casing, so that the air may escape around it. When the steam or vapor enters the third radiator section and heats the same, the heat at once raises the temperature of the coil 11 and the mercury or other fluid contained in the pipe 10 expands so that the diaphragm 8

will be caused to carry the valve 7 against the side of the vent tube and close the port 6. The further escape of air will thus be cut off and the pressure of the trapped air will prevent the steam flowing farther into the radiator. As the steam condenses, the temperature of the radiator will drop and the fluid in the pipe will contract whereupon the diaphragm and valve will move from the port 6. 10 Escape of air will then occur followed by the entrance of additional steam. The temperature of the room will thus be automatically maintained at the desired degree and the occupant will not be required to constantly open and close the supply valve 3. The handle 16 may be grasped to place the device at any point of the radiator and the spring 12 will firmly hold the device in place without the use of any hooks or other devices which 20 could not be detached without considerable labor.

The attachment may be utilized in connection with the radiators in general use, all that is necessary being to detach the usual vent or air escape valve and substitute therefor the vent 4.

In the form shown in Figs. 4, 5 and 6, the flexible pipe 20 is connected directly to the radiator at the end remote from the supply pipe and the free end of the pipe is equipped with a handle 21, which may be of asbestos or other heat-resisting material so that it may be freely grasped. A strap or bracket 22 is secured upon the pipe over a port 23, therein, 30 and a leaf spring 24 is secured to the pipe at a point diametrically opposite the casing to engage a radiator section and hold the casing against an adjacent section as shown in Fig. 4. A valve 25 is arranged to close the port 23 and said valve is carried by a thermostatic disk or diaphragm 26, secured on the inner side of the strap or bracket. In this arrangement, the heat from the radiator section acts directly on the thermostatic disk and expands 40 the same so that the valve is seated and the escape of air cut off, the operation being substantially identical with the operation of the previously described form.

Upon reference to Fig. 6, it will be readily understood that the air driven from the radiator and the pipe 20 escapes through the open space between the pipe and the diaphragm. To overcome the possible formation of a vacuum which would hold the valve 25 seated, 50 I provide an inwardly opening check valve 27, controlling a port in the handle 21. Should a vacuum tend to form atmospheric pressure will open the valve and break the vacuum. Obviously in this form of the invention, the entire thermostatic member is exposed to the action of the heat thrown off by the radiator section and it will, therefore, respond very quickly to variations in the temperature.

65 Having thus fully described my invention,

what I claim as new and desire to secure by Letters Patent of the United States, is—

1. The combination with a radiator, of a vent secured therein, a casing over said vent, a valve in the casing controlling the flow through the vent, a diaphragm in the casing carrying said valve, a flexible pipe leading into the casing, means for supporting the free end of the pipe in contact with a radiator section, and a thermostatic liquid in said pipe 75 exerting pressure upon said diaphragm.

2. The combination with a radiator, of a vent secured therein, a casing over said vent, a valve in the casing controlling the flow through the vent, a diaphragm in the casing 80 carrying said valve, a flexible pipe leading into the casing, the free end of the pipe forming a coil, a ring secured upon said coil, a handle connected to said ring, and a spring attached to the coil and adapted to bear 85 against a radiator section and hold the coil in contact with an adjoining radiator section.

3. The combination with a radiator, of a vent secured therein, a valve controlling the flow through the vent, a flexible pipe leading 90 to the valve, means for supporting the free end of the pipe in contact with a radiator section, and a thermostatic liquid in said pipe adapted to actuate the valve through expansion and contraction of said liquid, said liquid being heated directly at a point of contact of the supporting means with the radiator. 95

4. The combination with a radiator of a flexible vent pipe adapted to contain a thermostatic liquid connected with said radiator, a thermostatic valve adapted to be actuated by the expansion and contraction of said liquid in said pipe and controlling the vent in the radiator, and means for supporting the free end of the pipe in contact with the radiator section. 100

5. As a new article of manufacture, a device for attachment to the vent pipe of a radiator, comprising a flexible pipe, a thermostatic valve controlling the flow through said vent pipe, and means for supporting one end of said flexible pipe in contact with a radiator section, the other end of the flexible pipe adapted to be connected to the thermostatic valve controlling the vent of the radiator. 110

MAURICE FRANK HUTCHISON.
